E. E. CLARK

LINGERIE CLASP

Filed June 2, 1923

FIG. 1

FIG. 2

FIG. 3

Patented Apr. 7, 1925.

UNITED STATES PATENT OFFICE.

EMMA EVANS CLARK, OF HAMMOND, INDIANA, ASSIGNOR TO THE WILSON FASTENER COMPANY, OF CLEVELAND, OHIO, A CORPORATION OF OHIO.

LINGERIE CLASP.

Application filed June 2, 1923. Serial No. 642,899.

To all whom it may concern:

Be it known that I, EMMA EVANS CLARK, a citizen of the United States, residing at Hammond, in the county of Lake and State 5 of Indiana, have invented a certain new and useful Improvement in Lingerie Clasps, of which the following is a full, clear, and exact description, reference being had to the accompanying drawings.

This invention relates to lingerie clasps of the type wherein there is a U-shaped spring metal strip carrying adjacent its free ends a snap fastener adapted to hold the two limbs substantially parallel in use but enabling 15 their ready separation.

The present invention involves certain specific improvements on the structure shown in my Patent No. 1,383,906, issued July 5, 1921. Its object is to cheapen the 20 construction and at the same time render the clasp more certain in its action, and this I accomplish by providing a stud and socket snap fastener wherein the socket member has an internal spring adapted to engage the 25 stud, and by soldering each member to the inner face of one of the limbs of the U-shaped spring. I position the socket member and at the same time prevent the solder from passing into the interior and interfering 30 with the spring by making a cavity in one of the limbs of the metal strip and setting the dome of the socket member in such cavity. This cavity serves to retain the solder so that the socket member is easily 35 and effectively fastened in place.

The invention is illustrated in the drawings hereof, and hereinafter more specifically described, and the essential features are summarized in the claims.

In the drawings, Figs. 1 and 2 are plans 40 of the opposite faces of the lingerie clasp; Fig. 3 is a side elevation or edge view; Fig. 4 is an enlarged vertical section showing the two limbs of the clasp adjacent their free 45 ends and the two portions of the snap fastener separated; Fig. 5 is an inner face view of the socket member of the fastening and a portion of the limb to which it is attached.

In Figs. 1, 2 and 3, I have shown the body 50 of the clasp as comprising two substantially parallel limbs 10 and 11 and a bowed connection part 12. This body is made of spring sheet metal. One of the limbs, shown as the lower limb in Fig. 3, has an intermediate 55 portion 13 separated from the limb by longi-

tudinal slits and bowed upwardly to provide a spring portion, tending to clamp the fabric when the space within the clasp is filled. A suitable cavity 14 is provided in one of the limbs adjacent the end, being made by 60 forming an outward protuberance concentric with the semi-circularly curved end 16 of the limb.

The stud member 20 of the snap fastener as shown comprises a disk-like portion 21 65 having its extreme edge curled inwardly as at 22 and having centrally projecting from it a hollow stud 23 having an enlarged head and a narrow neck 24. The base 21 of this stud member has substantially the same 70 diameter as the width of the metal strip and is soldered to that strip with its outer edge adjacent to the extreme semi-circular end 17 of that limb of the body.

The socket member of the fastening 30 75 comprises a sheet metal cup curled inwardly at its edge as at 31 and having centrally a hollow inwardly projecting dome 32, the extreme end of which extends beyond the plane defining the extremity of the inwardly 80 curled edge. This dome 32 has an enlarged head portion 33 and a narrower neck portion 34. Through opposite sides of the neck portion are slots 35. Within the socket member is a wire spring 40 shown as having 85 a portion 41 extending circularly for somewhat more than a semi-circle, and then bending backwardly towards itself as shown at 42, and then bending in the opposite direction to provide two free legs 43 which 90 extend across the slots 35 and project into the space within the dome member of the socket, as shown particularly in Fig. 5. These springs are adapted to snugly engage 95 the head of the stud member and give back as it is forced into the socket and then by engaging the neck of the stud hold it effectively in place.

As heretofore stated, the end of the dome 32 of the socket member extends beyond the 100 plane of the edge of the socket. The cavity 14 in the limb 10 of the U-shaped strip is adapted to accommodate this projecting portion of the dome. By this means the cavity automatically positions the socket member 105 so that it may be secured in place with its outer edge substantially aligning with the semi-circular edge of the strip, the socket member preferably having a diameter substantially the same as the width of the strip. 110

The socket member is effectively secured in place by having its dome soldered to the strip, the solder for this purpose being illustrated at 50 in Fig. 4. The protuberance of the limb 10 provides very convenient means for holding this solder while it is molten. A small amount of solder is either first secured on the end of the dome or within the cavity, and then when the parts are in position heat is applied sufficiently to melt such solder, the limb having the cavity being at that time below the socket, and thus such protuberance forms on its then upper side a shallow cup to hold such molten solder until it cools and hardens. This enables the socket member, which is open as shown in Fig. 4 and has the internal spring, to be readily and effectively soldered to the limb without danger of the solder passing into the interior of the socket and interfering with the spring action.

My lingerie clasp may be very cheaply constructed, the fastening members being readily applied to the limbs. The clasp is neat in appearance and effective in service, the spring within the socket member serving to retain the stud member therein even though the limbs of the clasp embrace a considerable thickness of fabric and applying corresponding stress, tending to separate the free ends at the fastener. Furthermore, by accurately positioning the parts of the snap fastener as described adjacent the free ends of the strip, I am able to use a comparatively narrow strip without requiring a smaller fastener than is commercially practicable.

I have found that the metal body strip may be made very conveniently and satisfactorily of spring sheet brass, though other metal may be employed if desired. When brass is used I have found it very effective to secure the snap fastening members by solder as heretofore explained. However, with other materials the parts might if desired be secured by brazing or electrically welding.

Having thus described my invention, I claim:

1. A lingerie clasp comprising a U-shaped resilient body and a snap fastener comprising a stud rising from a base, and a socket member having an internal spring, said socket member and base being secured to the inner faces of the limbs adjacent their free edges.

2. A lingerie clasp comprising a U-shaped resilient body of metal, a snap fastener comprising a stud rising from a base and a socket member adapted to receive the stud, said base and socket member being permanently united to the inner faces of the limbs of the strip adjacent the free edges thereof.

3. A lingerie clasp comprising a U-shaped strip of metal, a stud member secured to the inner face of one limb of the strip, a socket member secured to the inner face of the other member of the strip and comprising a casing having a hollow internal dome member with slots on its opposite sides, and a spring housed within the casing and acting through the slots to engage the stud member.

4. A lingerie clasp comprising a U-shaped strip of metal and a snap fastener carried on the inner face of the limbs thereof for removably securing them together, said snap fastener comprising a stud secured to one limb and a socket member secured to the other, the socket member having an internal dome adapted to receive the stud, said dome projecting beyond the plane of the edge of the socket member, and the corresponding limb having a cavity to receive such projecting portion of the dome.

5. In a lingerie clasp, the combination of a U-shaped strip of metal, a stud member of a snap fastener secured to one limb of said strip and a socket member secured to the other limb, the socket member comprising a casing having an internal hollow dome projecting beyond the plane of the edge of the casing, and the corresponding limb of the strip having a cavity occupied by the dome, the dome being soldered to the limb within such cavity.

6. In a lingerie clasp, the combination of a U-shaped strip of metal, a snap fastener having a stud member, the base of which is soldered to the inner face of one limb of the strip adjacent the free end, and a socket member secured to the inner face of the other limb of the strip, said socket member having a cup-like casing with an internal dome projecting beyond the plane of the edge of the casing and the limb having a cavity to receive said dome, the socket member being secured with the edge of the casing contacting with the inner face of the limb, and a spring within the casing having portions occupying slots in the opposite sides of the dome, whereby the neck on the stud may be firmly clasped within the dome.

7. In a lingerie clasp, a pair of resilient arms, one arm being provided with a hole, a cup in the hole provided with lateral slots, a disk integral with the cup, a peripheral flange on the disk, a spring in the disk comprising a body engaging the flange and resilient fingers registering in the slots, a post fast to the other arm, and a head on the post registerable in the cup and engageable by the fingers.

In testimony whereof, I hereunto affix my signature.

EMMA EVANS CLARK.
